UNITED STATES PATENT OFFICE.

MALVIN LICHTER, OF NEW YORK, N. Y.

BUTTON.

1,178,738.

Specification of Letters Patent. Patented Apr. 11, 1916.

Application filed July 5, 1913, Serial No. 777,522. Renewed May 15, 1915. Serial No. 28,477.

To all whom it may concern:

Be it known that I, MALVIN LICHTER, a citizen of the United States, and a resident of New York, in the county of New York and State of New York, have invented certain new and useful Improvements in Buttons, of which the following is a specification.

This invention relates to buttons and particularly to that class known as detachable such as are used mainly for display purpose.

The object sought to be obtained is the provision of a button of this character made entirely of paper, hence of low constructive cost, but which will perform every function of a metallic button in displaying pictures, insignia, inscriptions and the like, and which may be readily applied or removed. This and other objects are accomplished by the novel construction and arrangement of parts hereinafter fully described and shown in the accompanying drawings, forming part of this specification, and in which:

Figure 1 is a perspective view of a button, made in accordance with the invention in its normal form ready for application. Fig. 2 is a vertical section of the same indicating its application. Fig. 3 is a perspective view of a modified form of button looking from the bottom, the shank being in an expanded position, and, Fig. 4 is a similar view of the same the shank or engaging means partially expanded.

The invention in its preferred form is comprised of three separate elements, each made of strong stiff paper or card board, the outer element or face 10 being of any preferred contour, as round, oval or polygonal, and of a size to present a desirable area which may be embossed, stamped or printed with any design compatible with its purpose.

A similar plate element 12 of like material and contour used as a backing, is secured to the back of the first element by suitable adhesives in such manner as to have the edges of both in register; these edges may obviously be crimped or covered with a band if preferred, for the purpose of greater security or finish but such treatment is not regarded as essential. The third or shank member is also of paper or cardboard in the form of a relatively narrow strip creased from side to side at the middle of its length 15, so as to bend or fold readily, other bending creases 16 being formed laterally across at uniform distances from the center, the

same providing arms 17 adapted to hold the button in position when adjusted; the strip is still further creased at 18, the portions 19 between the creases 16 and 18 forming engaging members adjoining which is a doubled shank 20 adapted to extend through the opening in the supporting article, while the end portions 21, are passed through a narrow slot 14 formed through the backing plate 12 and turned outwardly at the creases 22. These ends are preferably curved and when combined present substantially a circular disk that is secured between the backing plate 12 and face 10 by the mentioned adhesive.

In operation, the strip being folded on the central crease 15, so that it is doubled closely upon itself and extended perpendicular to the face of the button, forming a shank which is passed through a button hole, as in the lapel of a coat, until the backing plate contacts with the surface of the garment; the shank is then separated and expanded by folding the arms 17 and 19 outwardly on the creases 16 which action straightens out the crease 15 and folds the creases 16 acutely so that the arms 17, taken together present a straight face or preferably one with a slight concavity. This arrangement renders it impossible to disengage the button except by rupturing the parts by force applied at the head of the button, although disengagement may easily be effected by pressure applied to the projecting arms at the fold 16, causing them to collapse as by drawing the members 17 outwardly from the crease 15 or by turning the doubled arms 17 and 19 straight out and parallel, the same pivoting on the creases 18, and render it easy to withdraw the button shank.

The modification shown in Figs. 3 and 4 illustrate the invention in its simplest form, only two component parts being employed; the face 10 and a shank formed in every respect as before described; in this form the backing plate 12 is dispensed with and the shank ends 21 are secured direct to the rear of the face or display element by any suitable means.

It is to be noted that the inherent resiliency of the paper fabric will retain the button in an adjusted position indefinitely and furthermore that in normal condition the center part 15 cannot spring to free the button, as it would have to force the lapel away

from its ordinary position, which is usually closely adjacent to another portion of the garment; also that the button can be removed and inserted repeatedly without injury to the component parts and without defacing a garment as by pins and like common securing means.

Having thus described my invention, what I claim as new and desire to secure by Letters Patent, is:

1. A detachable button comprising a paper face and a paper shank, said shank being doubled and secured at its free ends to the rear of said face and provided with bending creases whereby it may be folded closely upon itself for insertion or removal and expanded by compression for maintenance when in position.
2. A detachable button comprising a display disk and a doubled paper strip having its free end secured to the rear of said disk, said doubled strip being adapted to pass through a button hole and the portion projecting therethrough be expanded.
3. As a new article of manufacture, a button of the class described formed wholly of

paper and comprising a face plate, a back-
ing plate and a doubled integral shank com-
bined therewith, said shank being adapted
to enter and engage with an ordinary but-
ton hole or be disengaged therefrom by
pressure applied in the direction of its
length.

4. A detachable button comprised of two
independent single disks of card-board, one
being superimposed upon the other, the
lower of said disks containing an elongated
aperture, and a card-board shank formed
of a single strip doubled upon itself and
having its free ends entered through the
mentioned slot and secured between the said
disks, the extending portion of said strip be-
ing so creased as to either fold flat perpen-
dicular to said disk or be extended laterally
and parallel to said disks.

In testimony whereof I have signed my
name to this specification in the presence of
two subscribing witnesses.

MALVIN LICHTER.
